UNITED STATES PATENT OFFICE.

GEORGE HENRY SMITH, OF PROVIDENCE, RHODE ISLAND, ASSIGNOR TO
THE BEAMAN & SMITH COMPANY, OF PROVIDENCE, RHODE ISLAND,
A CORPORATION.

HORIZONTAL SPINDLE DRILLING AND BORING MACHINE.

SPECIFICATION forming part of Letters Patent No. 718,956, dated January 20, 1903.

Application filed November 7, 1901. Serial No. 81,484. (No model.)

To all whom it may concern:

Be it known that I, GEORGE HENRY SMITH, a citizen of the United States, residing at Providence, in the county of Providence and State 5 of Rhode Island, have invented certain new and useful Improvements in Horizontal Spindle Drilling and Boring Machines; and I do declare the following to be a full, clear, and exact description of the invention, such as 10 will enable others skilled in the art to which it appertains to make and use the same, reference being had to the accompanying drawings, and to the letters of reference marked thereon, which form a part of this specification. 15

My invention relates to improvements in horizontal spindle drilling and boring machines; and it consists of the parts and combination of parts, as will be more fully here- 20 inafter described and shown.

In the drawings, Figure 1 is a top plan view of the character referred to embodying my invention, parts being broken away. Fig. 2 is a side elevation of the same, parts being 25 broken away.

B is the bed of the machine.

K is a platform on which the operator stands, which is supported in such manner on the traveling head G as to be rigid and still 30 be capable of sliding vertically when the head is at or near its lowest position, as will be hereinafter described.

The saddle E slides horizontally on the bed of the machine, and to this saddle the main 35 column or upright F is secured. The spindle-head G has a vertical sliding movement on the column F.

H represents brackets attached to the spindle-head G, each having yoke ends, each yoke 40 carrying two grooved guide-wheels M, journaled therein, between which the main supports I of the platform K are supported and guided as the platform moves.

The operator stands upon the platform K

when operating the machine. A stop N, se- 45 cured around the top of the supports I, rests on the supporting-brackets H H and limits the downward movement of the supports and the platform K. If, however, the head G is lowered to the saddle E, the platform K will 50 not strike the bed B, as the projection L will strike the saddle E and arrest the downward movement of the platform. The head G may continue to descend after the platform is at rest, as the supports I will slide upward be- 55 tween the guide M, the wheels moving downward on the supports until the head G is at its lowest position, the reverse action taking place on the upward movement of the head G, as will be readily understood from Fig. 2. 60

Braces O extend from the outer end of the platform above the brackets H, the upper ends being secured to the top N. O is a guard-rail secured around the platform.

Having thus described my invention, what 65 I claim, and desire to secure by Letters Patent, is—

1. In a machine of the character described, the combination with the bed and platen, and the movable spindle-head, of a platform, sup- 70 ports extending upwardly therefrom, brackets secured to the said head and guide-wheels secured in said brackets between which the said guides work.

2. In a machine of the character described, 75 the combination with the bed and movable spindle-head, of a platform movably mounted on said head and a projection extending from the platform adapted to engage said bed and arrest the downward movement of the plat- 80 form.

In testimony whereof I affix my signature in presence of two witnesses.

GEORGE HENRY SMITH.
